ATTORNEYS

UNITED STATES PATENT OFFICE.

ALONZO S. APPLEBY, OF ASH GROVE, MISSOURI.

LOCK.

SPECIFICATION forming part of Letters Patent No. 242,099, dated May 31, 1881.

Application filed April 4, 1881. (Model.)

To all whom it may concern:

Be it known that I, ALONZO S. APPLEBY, of Ash Grove, in the county of Greene and State of Missouri, have invented certain new and useful Improvements in Locks; and I do hereby declare that the following is a full, clear, and exact description of the invention, which will enable others skilled in the art to which it appertains to make and use the same, reference being had to the accompanying drawings, which form a part of this specification.

Figure 1 is a plan view of my improved lock, the cover being removed, so as to show the construction. Fig. 2 is a sectional view on the line *x x*, Fig. 1. Fig. 3 is a sectional view on the line *y y*, Fig. 1; and Fig. 4 is a sectional view on the line *z z*, Fig. 1.

Corresponding parts in the several figures are denoted by like letters of reference.

20 This invention relates to locks for doors, &c.; and it consists in certain improvements in the construction of the same, which will be hereinafter fully described, and particularly pointed out in the claim.

25 In the drawings hereto annexed, A represents the case of my improved lock, which is provided with a recess, B, for the vertically-sliding bolt or tumbler B', which is provided upon its front side or face with a diagonal groove, C, and some distance above the latter with a pin or stud, D.

30 E is the lock-plate, which slides in a transverse diagonal recess, F, in the case A, and which is provided with a transverse groove, G, in which works the pin or stud D of tumbler B'.

35 H H are a set of key-plates fitted in a recess, I, in the case A, adjoining recess B. The said key-plates, which are adjustable and interchangeable, are provided with openings I' for the admission of the key, and recesses J to enable the latter to be turned between the several plates, so as to eventually enter the lock.

The key, which is shown in the sectional

views of the drawings, consists of a stem or 45 shaft, K, having a suitably formed or constructed bit, L, adapted to enter through the suitably constructed and disposed key-plates.

From the foregoing description, taken in connection with the drawings hereto annexed, the 50 operation and advantages of my invention will be readily understood.

The key-plates H may be adjusted or interchanged in any suitable manner, so as to change the combination or the way in which it is necessary to turn the key in order to open the lock. When the key passes through the key-plates it enters the diagonal groove C in the tumbler, and being pushed farther in raises the latter and the lock-plate, thus allowing the 60 door to be opened. When the key is removed the tumbler drops down by its own weight, carrying with it the latch, and thus locking the door.

My improved lock is eminently simple in its 65 construction, and it may be constructed of wood or any other suitable material by any one knowing how to use the simplest tools. When made of wood, rust and other incidental damage is prevented, and as a lock for the doors of 70 barns, granaries, and other out-buildings it is exceedingly desirable.

Having thus described my invention, I claim and desire to secure by Letters Patent of the 75 United States—

The combination, with the case A, having gravity-tumbler B', provided with diagonal slot C and stud D, and interchangeable key-plates H H, having openings I' and recesses J, of the transversely-slotted lock-plate E and key 80 K, as herein described, for the purpose set forth.

In testimony that I claim the foregoing as my own I have hereto affixed my signature in presence of two witnesses.

ALONZO SUSTAN APPLEBY.
